UNITED STATES PATENT OFFICE.

MATTHEW MORTON AND HENRY E. MORTON, OF MUSKEGON HEIGHTS,
MICHIGAN.

SLOTTING-MACHINE.

SPECIFICATION forming part of Letters Patent No. 757,562, dated April 19, 1904.

Application filed July 29, 1902. Serial No. 117,464. (No model.)

To all whom it may concern:

Be it known that we, MATTHEW MORTON and HENRY E. MORTON, citizens of the United States, residing at Muskegon Heights, county 5 of Muskegon, State of Michigan, have invented a certain new and useful Improvement in Slotting-Machines, of which the following is a specification, reference being had to the accompanying drawings, which form a part of 10 this specification.

Our invention has for its object to provide an improved slotting-machine, the same being more particularly designed for cutting out the material and finishing the openings in solid- 15 end connecting-rods, double-throw cranks, and other work of this nature, although we do not limit ourselves solely thereto.

Our invention consists of the construction, combination, and arrangement of devices 20 hereinafter described and claimed, and illustrated in the drawings, in which—

Figure 1 is a view in side elevation, parts being in vertical section. Fig. 2 is a view in elevation at right angles to Fig. 1. Fig. 3 is 25 a plan view of the machine. Fig. 4 is a view in vertical section showing parts in elevation. Fig. 5 is a partial vertical section on the line 5 5, Fig. 3, showing features of the invention. Fig. 6 is a partial vertical section on the line 30 6 6, Fig. 5. Fig. 7 is a detail view in section of certain features of the automatic feed-gear and pawl. Fig. 8 is a view of the same in side elevation, parts being broken away. Fig. 9 is a view in side elevation showing the side 35 opposite that shown in Fig. 1, certain features shown below the turn-table in Fig. 1 being omitted. Fig. 10 is a view in rear elevation showing the side opposite that illustrated in Fig. 2, omitting the truck *l* and features 40 mounted thereupon.

In certain kinds of heavy work, as in cutting out the material or slotting and finishing the solid ends of connecting-rods, it becomes necessary either to turn the work or the machine, so that the work may be cut in different directions.

To this end our invention contemplates turning the machine and adjusting the same relative to the work as being more convenient 45 and desirable than to turn the work.

We carry out our invention as follows:

In the drawings, *a* represents a turn-table; *b*, any suitable bed serving as a circular track, said track supported upon a foundation *c*. The turn-table is provided with a gear *d*. Upon 55 the foundation is supported a shaft *e*, provided with a pinion *f*, meshing with a gear *g* upon a shaft *h*, said shaft provided with a pinion *i*, meshing with the gear *d*. The shaft *e* is shown provided with a hand-wheel *j* to actuate 60 the same and revolve the turn-table.

Upon the foundation *c* are located tracks *k*, upon which is mounted a truck *l*, provided with wheels *m* to travel upon said tracks. Upon the truck is a carriage *n*, arranged to 65 travel transversely of the travel of the truck, the truck being provided with tracks *p*, supporting said carriage. By means of this truck and carriage we are enabled to feed the work to the machine in either direction—*i. e.*, to- 70 ward or from the machine—and in a transverse direction. The work is indicated at *q*. The work may be held upon the carriage *n* in any suitable manner, as by a clamping device 1, and may be vertically adjusted there- 75 upon in any desired manner, as by an adjusting-screw 2.

Upon the turn-table is located a fixed sup- 80 porting frame or base *r*, provided with a bed *s*. A lateral feed-table *t* is mounted upon the bed *s*. Upon the table *t* is a cross feeding-table 10, the upper side of which is circular and provided with a circular T-slot 23. Upon this cross feeding-table is movably mounted a re- 85 volving chuck or mechanism to hold the work, said chuck being provided with a rotatable table 11 and with adjustable jaws 12. The table 11 is engaged upon the table 10 by means of bolts entering the T-slot thereof, as shown. The jaws 12 are adjustable for the purpose of 90 receiving larger or smaller connecting-rods. By loosening the bolts which secure the table 11 upon the table 10 the table 11 may be re- 95 volved in either direction. A cutter-bar is indicated at *w*, preferably engaged in a cross- head *x*, provided toward its lower end with a rack-bar *y*.

Certain features of construction embraced in our improved connecting-rod-slotting machine were embodied in United States Letters 100

Patent granted February 7, 1899, No. 618,894, such as a tilting frame 3, having a jointed engagement toward its base with the fixed frame or column *r*, as at 4. The particular construction and arrangement of the fixed frame and of the tilting frame, with their related parts, are set forth in the Letters Patent above referred to.

With this special machine it is necessary 10 for the cutter to reciprocate, and to provide a reciprocating motion a suitable train of gears *u* and a belt-shifting device are supplied, said train of gears being driven by any suitable source of power, as a motor *v*, the train of 15 gears actuating said cutter-bar.

Referring to Fig. 10, the back side of the column *r* is shown provided with three pulleys mounted upon a shaft 52, the outer one representing a tight pulley which is keyed to the 20 shaft, which is used for the purpose of driving the machine in the cut. The intermediate pulley is loose. The inner pulley for driving on the return stroke is attached to the hub of a pinion 49, which meshes directly into the 25 main driving-gear of the machine and revolves freely on shaft 52. When power is applied to the pulley for driving the machine on the cut, it is transferred through shaft 52 to a pinion 50, from thence to an intermediate gear 30 54, through to a pinion 51, thence on to the main driving-gear of the machine. When the cutting stroke is completed, by the employment of reverse mechanism 44, working in conjunction with tappets on circular disk 45 35 and reversing dog or cam 48 and connections, the belt-shifter is made to throw the belt to the opposite driving-pulley, the power then being applied directly to the gear 49 upon the driving-shaft 6, thence to the main driving-gear 40 of the machine, and the cutter-bar, cross-head, &c., are made to travel in the opposite direction with a quick return ratio, as is represented by the difference in the diameters of the pinion 50 and intermediate gear 54. 47 45 represents a friction-clutch for stopping and starting the machine at any part of its stroke.

The preferred power for this machine is an electric motor belted direct. The main driving-gear is attached to the shaft, which is provided with a pinion which engages a rack-bar or toothed portion *y*, secured to the cross-head, in which the reciprocating cutter-bar *w* is preferably engaged and by which it is carried in its reciprocating motion. A pinion 55 upon the driving-shaft 6 meshes with the bar *y*, said shaft being actuated by the system of gears *u*.

Upon the bed of the tilting frame 3 is supported a post 7, toward the top of which is 60 engaged an arm 8, projecting forward against the cutter-bar to form a support for the upper end of said bar to prevent the cutter-bar from springing away from the work. This arm may be made adjustable in any suitable 65 manner, as indicated in the patent above re-

ferred to, while the post 7 may also be made adjustable, as indicated in said patent.

The work is laid in a horizontal position and the slotting mechanism is revolved on the foundation *l*, so that the cut may be made 70 in any desired direction, the line of work *q* lying parallel with tracks *k*, thereby effecting a great saving of room, as well as increasing the efficiency in operation and adjustment. It will be understood that the pump 19 is arranged to take the fluid for lubricating the cutter, and by means of pipes, &c., it forces the fluid on the cutter while making its operation, receiving its power from an eccentric on the intermediate gear-shaft 46. The arrangement is such that the oil or fluid is allowed to run into receiving-box 20, and the pump takes it from this box and places it on the cutter. It will also be understood that the cutter-bar 75 is movable with the tilting frame, whereby said cutter-bar may be tilted to any desired angle, although for the particular work for which this machine is designed it is not necessary to have any given amount of adjustment.

An automatic cutter-bar-relieving mechanism is provided in the form of an eccentric and shaft 53, the same being actuated by reversing dog or cam 48 and intervening connections, the main feed-lever 26 being journaled on the upper end of the eccentric and 85 shaft 53. As the dog or cam 48 moves in either direction to actuate belt-shifter 55 the eccentric-shaft 53 makes a portion of a revolution, whereby lever 26 is withdrawn from contact with tilting frame 3. This allows the 90 cutter to drop back on its return stroke, thereby preserving its edge, and when the machine automatically reverses for its cutting stroke the eccentric-shaft 53 is drawn in the opposite direction, forcing lever 26 and tilting 105 frame 3 and cutter-bar *w* to the desired position to take its cut, there being a bar 24 connected at one end to the lever 26, and its other end is adapted to bear against the back of the cutter-bar, as shown in Fig. 4.

The provision of the lateral feed-table *t*, the cross feed-table 10, and the revolving table 11 for the chuck enables us to adjust the chuck in any desired position. These tables are fed either automatically or by hand, as will appear from the following description: Beneath the table *t* is a threaded hanger 13^a, with which a threaded shaft or screw 13 engages, as shown in Figs. 5 and 6. On the end of this screw 13 is a bevel-gear 14, which meshes with a similar gear 14^a, secured to a shaft 27, which is journaled in a bearing on the side of the bed *s*. (See Figs. 2 and 3.) On the end of the shaft 27 is a gear 35, which meshes with a gear 31 on an axially-oscillatory shaft 29, 115 said shaft being journaled in the bed *s* and extending parallel with the shaft 27, which it drives. Oscillatory movements are imparted to this shaft 29 by means of a crank 17, secured to the opposite end of the shaft, the 120 125 130

crank being connected to a friction-clutch 18 by a pitman 28, as shown in Fig. 1. The clutch 18 is operated by the driving mechanism in the usual way, and through the adjunctive mechanism above described the screw-shaft 13 feeds the work to the cutter.

In order to provide a progressive or step-by-step feed for the work, which feed takes place at the completion of the cutting stroke, 10 I provide a pawl-and-ratchet mechanism between the axially-oscillatory shaft 29 and the gear 31, such as is shown in Figs. 7 and 8. Keyed to the shaft 29 is a disk 30, carrying a pawl 21, which has toothed extremities 33 and 34, and secured to the gear 31 is an internally-toothed ratchet 32, which when the pawl is turned to engage it receives an intermittent rotary motion. The gear 31 is preferably journaled loosely on a collar 31^a on the shaft 29. By this construction it will be seen that the table *t* may be fed either automatically or by hand, and the latter operation will not affect the position of the shaft 29 or its operating means, since the pawl 21 may be turned so as 20 to slide around the ratchet, and then by applying a crank or wrench to the angular end of the shaft 27 the feed-screw 13 may be rotated. Similar mechanism is employed for feeding the work in a direction at right angles to the movement imparted by the feed-screw 13, the movement being imparted to the table 10. The feed-screw 22 for this table has one end secured in the table, as seen in Fig. 5. The gear 35 is detachably mounted 30 on the shaft 27 and may be removed and placed on a shaft 15, when it will mesh with the gear 31, and the shaft 15 will then be driven in the same manner as the shaft 27. This shaft 15 extends through the bed *s* and has a bevel-gear connection 16 at its opposite end with a shaft 36, journaled in a bearing 42. (Shown in Figs. 1 and 3.) This shaft has a bevel-gear which meshes with a bevel-gear 37 on one end of a shaft 38, (see Figs. 2 and 10,) 40 and on the other end of the shaft 38 is a gear 39, meshing with a gear 40, which drives gear 41. The last gear has a threaded engagement on the feed-screw 22, but is stayed against longitudinal movement by a band 41^a, connected 45 to the frame or bed *s*, whereby the feed-screw is moved longitudinally through the gear 41 and the table 10 shifted. It will be apparent that the table 10 may be fed by hand by applying a crank or wrench to the angular 50 end of the shaft 15.

It will be evident that by the provision of the feed-screws 13 and 22 the cross-plate 10 is adjustable in both directions, while by means of the hand-wheel *j* the revolving plate *a* may 55 be turned into any desired position. By means of the truck *l* and the carriage *n* the work may be operated in either direction.

19 represents an oil or water pump, and 20 represents an oil or water reservoir.

The mode of operation is as follows: A hole 65 is drilled through the solid end of the rod to be machined in two opposite corners. These holes are squared with a special bar and cutter for the purpose, these openings being sufficient to allow the cutter-bar and cutter *w* to 70 pass through them. The cutter in this case is enough wider than the bar to give perfect clearance to the bar. The cut is then taken across one end of the opening. The machine is then adjusted by hand back to the place of 75 the beginning. The bolts in the circular plate 11 are loosened and by turning hand-wheel *j* the machine is then revolved around a distance of ninety degrees and adjusted so that the cutter-bar *w* will pass through the opening. 80 The proper adjustments are then made as to alinement of cutter, &c., the work *q* remaining in its original position, and a cut of a little greater width than the bar is made along the side of the connecting-rod. After 85 this operation the cutter-bar is withdrawn, the circular plates loosened, the machine revolved by hand-wheel *j* another ninety degrees and adjusted. Then the cutter-bar may be placed through the hole prepared for this purpose, 90 and a cut is then taken down the end of the opening. After this operation it is returned by hand and the bolts loosened and hand-wheel *j* revolved, so as to turn the machine another ninety degrees, the cutter-bar replaced and adjusted, and a cut taken in this direction to the original point of beginning, thereby having cut out a solid chunk of metal and leaving a reasonably perfect opening in the end of the work *q*. 95

100 Other forms of tools may be substituted by which other classes of work may be machined with this machine.

The object of the adjustable carriage located on track *k* will be readily seen is to support the end of the work *q*, and in the operation of feeding the only movement the work *q* requires is to feed either laterally or to and from the cutter, and the supporting-carriage and track being self-adjusting in either direction makes it unnecessary to materially change the position of the work *q* while in its operation. 110

115 For purpose of illustrating, if the work were to be machined in the old way it would necessitate the moving of the work in the different positions hereinbefore referred to and if the work were eighteen feet long would take up a space covered by eighteen feet radius. This illustrates clearly the advantage 120 of having the work remaining in one position and overcomes the necessity of occupying so much room in doing this class of work.

57 denotes the end of the connecting-rod or work, and 58 binder-blocks for the same. 125

What we claim as our invention is—

1. In a slotting-machine the combination of a turn-table, a base supported thereupon, hori-

- zontally-adjustable mechanism for holding the work carried by said base, and a reciprocatory cutter carried by said base.
2. In a slotting-machine the combination of 5 a supporting -foundation, a turn -table supported upon said foundation, a supporting-base located upon said turn-table, a reciprocatory cutter carried by said base and driving mechanism to actuate said cutter, said driving mechanism located below the turn-table.
3. In a slotting-machine the combination of 10 a turn-table, a support therefor, a supporting-base located upon the turn-table, a reciprocatory cutter carried by said base, horizontally -adjustable work -feeding mechanism mounted upon said base, and means upon said support geared with the turn-table to actuate the same.
4. In a slotting-machine the combination of 15 20 a support having a countersunk portion or well, a turn-table carried by said support, a supporting-base upon the turn-table, cutter mechanism carried by said base, revolving mechanism to engage the work mounted upon said base and driving mechanism located in the countersunk portion or well of the support to drive the cutter mechanism.
5. In a slotting-machine the combination of 25 30 a turn-table, a supporting-base carried by the turn -table, an additional turn -table at the upper end of said base to engage the work, and cutter mechanism carried by said base, whereby the cutter mechanism may be turned and operated without moving the work.
6. In a slotting-machine the combination of 35 a turn-table, reciprocatory cutter mechanism, means to adjust the cutter mechanism relative to the turn-table, and means to carry one end of the work, said means movable toward and from the cutter mechanism, and in a trans- 40 verse direction.
7. In a slotting-machine the combination of 45 a turn-table having a vertical axis, horizontally -adjustable cutter mechanism carried thereby, a truck movable toward and from the cutter mechanism, and a carriage mounted upon said truck to support the work movable in a direction transverse to the movement of the truck.
8. In a slotting-machine the combination of 50 55 a turn-table, a base thereupon, a reciprocatory cutter carried by said base, a laterally -adjustable feed-table upon the upper portion of the base, a cross feed-table adjustable upon the lateral feed-table in a direction transverse to the movement of the lateral feed-table, a revolving plate upon the cross feed-table, and means for holding the work upon the revolving plate.

In testimony whereof we have signed this 60 specification in the presence of two subscribing witnesses.
